E. B. STONE

CABINET LOCK

Filed July 11, 1922

INVENTOR
Elmer B. Stone,
by
Arthur B. Jenkins,
ATTORNEY

UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

CABINET LOCK.

Application filed July 11, 1922. Serial No. 574,271.

To all whom it may concern:

Be it known that I, ELMER B. STONE, a citizen of the United States, and a resident of New Britain, in the county of Hartford, 5 and State of Connecticut, have invented new and Improved Cabinet Locks, of which the following is a specification.

My invention, while not limited in its uses, relates more particularly to the class of 10 locks provided for securing a number of closures, as drawers in a file cabinet, and an object of my invention, among others, is to provide a lock mechanism that shall be simple in construction and particularly effective in operation.

One form of lock mechanism embodying 15 my invention and in the construction and use of which the objects herein set out, as well as others, may be attained, is illustrated 20 in the accompanying drawings, in which—

Figure 1 is a view in vertical section on a portion of a plane passing lengthwise through the drawers of a drawer cabinet provided with my improved locking mechanism.

Figure 2 is a view in vertical cross section on a plane denoted by the dotted line 2—2 of Figure 1.

Figure 3 is a fragmentary view showing 30 the front upper left hand corner of a cabinet illustrating the position of the lock.

Figure 4 is a perspective view of a fragment of a cabinet illustrating the construction and operation of my improved lock.

Figure 5 is a detail view, scale enlarged, 35 illustrating the operation of the locking bolt.

Figure 6 is a view in cross section on a plane denoted by the dotted line 6—6 of Figure 5.

In the accompanying drawings the numeral 40 5 indicates the top, 6 one side, 7 the head piece, 8 a stile or side post, 9 the back and 10 the drawers of a file cabinet, all of which may be of any ordinary and well known construction, the drawers being mounted for 45 sliding movement in a manner common to devices of this class and for which reason a showing as to such mounting is omitted from the drawings herein.

The drawer locking mechanism comprises 50 a locking lug 11 projecting from the side of each drawer for engagement with a locking latch 12 pivotally attached to a latch fixture 13 supported upon and carried by a drawer locking bar 14 slidably mounted on brackets

15 secured to a side 6 of the cabinet, the latches being spring pressed into engagement with the lugs 11, as shown in Figure 1 of the drawing, and the noses of the latches being beveled to permit the lugs 11 to press the latches to one side whenever the drawers are moved to a closed position when the locking bar is in its locked position. All of the drawer locking mechanism thus far described is also old and of well known construction and further description and extended illustration are omitted herein.

In adapting my invention to the structure above described, I provide an offset 16 at the upper end of each locking bar 14 that engages with a guide 17 secured to the inner surface of the side 6 of the cabinet. A cam arm 18 is secured to the offset 16 and projects upwardly and forwardly into a cam notch 19 formed in the side of a locking bar actuator 20. This locking bar actuator is mounted for sliding movement in a box 21 secured to the under surface of the top 5 and near one side thereof, as shown in Figure 2 of the drawings. This actuator is normally 75 pressed forward, or toward the front of the cabinet, as by a spring 22 thrusting with one end against a spring seat 23 extending across the end of the box and into slots in the side thereof, as shown in Figure 4 of the drawings.

An actuator locking bolt 24 is located 80 preferably in the under surface of the actuator and projects therefrom into a keeper recess 25 in the bottom of the box 21. This locking bolt is actuated by lock mechanism 85 of any ordinary construction contained within a barrel 26 projecting from the end of the actuator 20 and having a key cylinder 27 of any ordinary form and construction to receive a key for the purpose of operating the locking mechanism. This key cylinder, barrel locking mechanism therein and its connection with the locking bolt 24 to operate the latter will be readily understood by anyone 90 skilled in the art and for this reason a further and detailed description is omitted herein.

The operation of the mechanism will be 95 readily understood, it being noted that when the locking mechanism is operated by means of a key in the key slot in the key cylinder to withdraw the locking bolt 24, the spring 22 will force the actuator 20 forwardly, carrying the locking bolt from registering 100 105 110

- position with the recess 25. This forward movement of the actuator will operate upon the cam arm 18 and thereby force the locking bar 14 downwardly, carrying the latches 12, appurtenant to each of the drawers, out of engagement with the locking lugs 11, and each drawer may, therefore, be readily opened. In its forward position the front end of the actuator preferably projects beyond the front of the cabinet, as shown in dotted lines in Figure 1 of the drawings. Pressure upon this end of the actuator, as by the thumb, will move the actuator backwardly into its locking position, in which position the locking bolt 24 will automatically move into the recess 25, in a manner that will be readily understood, thus holding the actuator in its rearward or locking position. This operation will lock only the drawers that may be closed, against opening movement. The drawers that are opened, however, may be closed, and when so closed the lugs 11 thereon will automatically engage the latches 12 and thereby lock the drawers in their closed positions and they can be again opened only by operation of the locking mechanism, as hereinbefore described. The cam arm extends through a slot in the bottom of the box, as shown in Figures 2 and 4 of the drawing.
- In accordance with the provisions of the Patent Statutes I have described the principles of operation of my invention, together with the device which I now consider to represent the best embodiment thereof; but I desire to have it understood that the device shown is only illustrative, and that the invention may be carried out by other means and applied to uses other than those above set out.
- I claim:—
1. In a lock mechanism, a movably mounted actuating member and an actuator member of a lock mechanism, mechanical means for operating said actuator member, a cam arm rigidly connected with and projecting from one of said members into engagement with the other of said members to be actuated by the movement of the actuator member under the influence of said mechanically operated means to operate said actuating member, and means for securing said actuator in its locked position.
  2. In a lock mechanism, a movably mounted actuator, mechanical means for operating said actuator, a member of a lock mechanism having a cam arm rigidly connected with and projecting therefrom into engagement with said actuator to be actuated thereby under the influence of said mechanically operated means, and means for securing said actuator in its locked position.
  3. In a lock mechanism, a movably mounted actuator having a cam groove, mechanical means for operating said actuator, a member of a lock mechanism, a cam arm rigidly connected with and projecting from said member into said groove to be actuated thereby under the influence of said mechanically operated means, and means for securing said actuator in its locked position.
  4. In a lock mechanism, a movably mounted actuator, mechanical means for moving said actuator, a member of a lock mechanism, connecting means between said member and said actuator for operating the former by movement of the latter under the influence of said mechanical means, and key operated lock mechanism mounted in and carried by said actuator for securing it in its locked position.
  5. In a lock mechanism, a movably mounted actuator, mechanical means for forcing said actuator in one direction, a member of a lock mechanism, connecting means between said member and actuator for operating the former by movement of the latter under the influence of said mechanical means, and key operated mechanism mounted in and carried by said actuator and including a locking bolt for locking the actuator in its closed position.
  6. In a lock mechanism a slidably mounted actuator having a cam slot in its side, mechanical means for imparting sliding movement to said actuator, a sliding bar having a cam projecting therefrom into said slot for operation of said member by the sliding movement of said actuator, said bar having means to engage members to be locked to secure them in closed position, locking means for holding the actuator in locked position, and key operated means for releasing said locking means.
  7. A lock mechanism, a movably mounted actuator, a member of a lock mechanism operatively connected with said actuator, and a key actuated locking mechanism mounted in and carried by said actuator and including a locking member movable independently of said key actuated mechanism for automatically securing said actuator in its locked position to prevent movement of said member.

ELMER B. STONE.
